(57) **CLAIM**

The ornamental design for a combined earphone and charger, as shown and described.

DESCRIPTION

FIG. 1 is a perspective view of a combined earphone and charger showing my new design, the charger is shown separately for ease of illustration;

FIG. 2 is a front elevational view thereof;

FIG. 3 is a rear elevational view thereof;

FIG. 4 is a left side view thereof;

FIG. 5 is a right side view thereof;

FIG. 6 is a top view thereof;

FIG. 7 is a bottom view thereof;

FIG. 8 is a perspective view thereof, showing the combined earphone and charger in a closed position;

FIG. 9 is a perspective view thereof, in an open configuration;

FIG. 10 is a perspective view of earphone of combined earphone and charger, shown separately for ease of illustration;

FIG. 11 is a front perspective view thereof;

FIG. 12 is a rear perspective view thereof;

FIG. 13 is a left side elevational view thereof;

FIG. 14 is a right side elevational view thereof;

FIG. 15 is a top view thereof;

FIG. 16 is a bottom view thereof; and,

FIG. 17 is another perspective view.

The broken lines depict portions of the combined earphone and charger forms no part of the claimed design.
